STIRRER

Otto W. Dieffenbach, Jr., Towson, Md., assignor to
Glassips Inc., Baltimore, Md., a corporation of
Maryland

Filed Jan. 11, 1968, Ser. No. 10,135

Term of patent 7 years

U.S. Cl. D44—29
Int. Cl. D7—03

FIG.1.

FIG.2.

FIG.3.

FIG.4.

FIGURE 1 is a front elevational view of a stirrer showing my new design;

FIGURE 2 is a side elevational view;

FIGURE 3 is a top plan view; and

FIGURE 4 is a sectional view thereof on line 4—4 of FIGURE 1.

The rear of the stirrer is the same as the front.

The characteristic features of my design for stirrer reside in its undulating form in one plane only and in the contrastingly colored straight stripes on the opposite straight sides of the stirrer, all as shown.

I claim:

The ornamental design for a stirrer, as shown and described.
